UNITED STATES PATENT OFFICE.

RICHARD CAFFREY; OF SOUTH BETHLEHEM, PENNSYLVANIA.

DESIGN FOR A RAILROAD-TIE PLATE.

SPECIFICATION forming part of Design No. 26,843, dated March 30, 1897.

Application filed February 18, 1897. Serial No. 624,062. Term of patent 14 years.

To all whom it may concern:

Be it known that I, RICHARD CAFFREY, a citizen of the United States, residing at South Bethlehem, in the county of Northampton and State of Pennsylvania, have invented and produced a certain new and original Design 5 for a Railroad-Tie Plate, of which the following is a specification, reference being had to the accompanying drawings, forming part hereof, in which—

Figure 1 is a perspective view of the top of the tie-plate, showing the particular shape or configuration thereof. Fig. 2 is a similar view of the bottom of the plate, and Fig. 3 is a longitudinal sectional view through the same, these three views being deemed essential to fully show the particular features of the design of the plate of my invention.

The leading feature of my design consists 20 of a body portion made slightly tapering in cross-section, with perforations extending therethrough beyond both ends for the reception of stays or spikes, one or more of the perforations being located in the plain surface of the body of the tie and the other being located in and extending through the body portion and rib or projection extending crosswise of the plate inside of the end of the plate, which at that point terminates in a 25 downwardly-projecting beveled cross wedge or rib, and beyond the center of the plate on the under side of the same and in the direction of the end which is not provided with a 30 beveled cross wedge or rib is cast or molded

with the plate a bevel or chisel-like projecting rib.

Referring to the drawings, A is the rectangular - shape body portion of the tie-plate, made slightly tapering in cross-section from one end to the other of the same, as clearly 35 illustrated in Fig. 3. At one end the plate terminates in a downwardly-projecting cross-beveled or chisel-like wedge or rib a, and inside of this end of the plate on the upper surface and integral therewith is cast or molded 40 a recessed and curved cross-rib b, perforated at b', and which perforation extends through the body of the plate A. On the under side of the plate and beyond the middle thereof and in the direction of the slightly-tapering 45 end a' is provided a downwardly-beveled or chisel-like wedge or rib c, and near to this last-mentioned end of the plate A at required distance apart is or are provided one or more 50 perforations d, extending clear through the 55 said plate A for the insertion of stays or spikes.

Having thus described my invention, what I claim as new, and desire to secure by Letters Patent, is—

The design for a railroad-tie plate, substantially as shown and described.

In testimony whereof I have hereunto set my signature in the presence of two subscribing witnesses.

RICHD. CAFFREY.
